RUDOLPH W. EVANS, OF HAMILTON, ONTARIO, CANADA, ASSIGNOR TO ROBERT N. EVANS, OF HAMILTON, ONTARIO, CANADA.

ANTISKID CHAIN.

1,420,533.

Specification of Letters Patent. Patented June 20, 1922.

Application filed April 10, 1920. Serial No. 372,925.

To all whom it may concern:

Be it known that I, RUDOLPH W. EVANS, a citizen of the United States, residing at Hamilton, Province of Ontario, and Dominion of Canada, have invented certain new and useful Improvements in Antiskid Chains, of which the following is a specification.

This invention relates to anti-skid chains, particularly adapted for motor vehicle wheels, it more particularly relating to an improved cross chain therefor, comprising a plurality of inexpensively and readily formed side links and an improved center link, which can be readily threaded through a pair of such side links and which is likewise inexpensively and readily formed and is very efficient and durable in use.

In the drawings accompanying and forming a part of this specification, Fig. 1 is a perspective view of a side link in the flat; Fig. 2 is a perspective view of the center link in the flat; Fig. 3 is a perspective view of the center link having its projections or lugs bent upwardly; Fig. 4 is a perspective view of this improved center link showing an increased number of bendable projections; Fig. 5 is a perspective view illustrating the projections of Fig. 4 upwardly bent; Fig. 6 is a perspective view illustrating the center link shown in Fig. 4 with its eye-forming projections partially bent and its side projections or lugs also bent; Fig. 7 is a perspective view of the center link shown in Figs. 2 and 3 partially assembled with a pair of side links; and Fig. 8 is a perspective view of a completed cross chain attached to portions of a pair of side chains. Fig. 9 is a detail view of one of the end hooks.

Similar characters of reference indicate corresponding parts in the several figures of the drawings.

The improved side link 2 herein shown is blanked or stamped flat out of a strip of steel of substantially the width of the completed link and the operator, by means of a die, first cuts out the two triangularly shaped or key-hole slots 3 in the ends of the blank flat link and then as the link is moved forward the operator cuts the concaved sides

4 forming the relatively narrow intermediate portion 5 and at the same time cuts the rounded ends 6 of the link thus completing the shape of the link in readiness to be bent in the manner shown in Figs. 7 and 8, in 55 which the two flat portions of the link are bent into parallelism to form an eye 7 for the reception of a center link and an eye 8 extending transversely to the eye 7 for the reception of a companion side link or hook 60 9 as the case may be.

In practice, each side line may have the bent portion forming the eye 8 slightly concaved or curved to prevent wear as much as possible. It will be observed furthermore, 65 that the narrow portions of the slot 3 are adjacent to the concaved side edges of the link, so that the link is not materially weakened adjacent to such concaved side edges while such concaved side edges form a narrow intermediate portion, which will fit the enlarged ends of the slots 3 and also receive the eye-forming projections of the center links.

In assembling, each side link according 75 to the number used is first threaded through the slots 3 of a companion side link and then has its two widened ends compressed in the manner shown in Fig. 7 while each end link of each cross chain may be first threaded through the hook 9 and then have its ends compressed in a similar manner or the hooks may be passed through the eyes of the end links after they are completely assembled as may be found preferable in practice. 85

In bending the side links transversely of their length to form the eyes 8, the two flat slotted portions of the link are brought together in such manner that the two narrow bent portions forming the eye 8 are so spaced 90 apart that the outer sides of these portions will project beyond the flat portions or ends of the side link and thus make the side link somewhat flexible and in practice it is not essential that the flat portions carrying the 95 slots 3 be brought into engagement throughout the entire flat portions of the link, it being sufficient and more desirable to have the ends only of the flat portions in contact as at 10, Fig. 7.

The improved center link 12 is likewise stamped or blanked from a flat strip of steel substantially in the manner shown in Figs. 2 and 4 according to the number of locking 5 projections desired, the eye-forming projections 13 and locking projections 14 all being formed at the same time. The eye-forming projections 13 are provided with enlarged I-shaped or T-shaped ends 15, thus 10 providing narrower eye-forming portions when the center link is completely formed while the body 16 of greater width than the narrow or neck portions 13, is provided with a plurality of projections 14 and 15 notches 17. After the formation of the 15 center link in the manner described, the locking projections 14 are bent upwardly as shown in Figs. 3 and 5 in readiness to receive the bent eye-forming ends of the 20 link, which are bent into the position shown, for instance, in Figs. 6 and 7, and then the side links are assembled therewith as shown in Fig. 7 and then the eye-forming projections 13 of the center link are compressed 25 in such manner that the locking projections 14 may be bent or compressed thereover as shown in Fig. 8. In bending or compressing the parts of the center link the body 16 of the link is curved at each 30 side somewhat in the direction of its length so that a portion of each pair of end projections will overlap the inner edges of the T or I-formed heads of the eye-forming projections 13, and thus prevent them from 35 pulling out while the overlapping of the heads of the portions 13 by the locking projections 14 will prevent the separation of these projections 13 from the body of the link 16. The center link is also bent transversely of its length to conform to the shape 40 of the shoe. The flattening of the locking projections 14 is obtained by placing the center link in a press and firmly bending down the projections 14 over the heads 15 of the center link, and the center link is also placed in a press and the two sides or edges 45 thereof are so bent that the end locking projections 14 will be bent around or over the inner edges of the heads thus to prevent, 50 as hereinbefore stated, the pulling out of the heads in the direction of the length of the cross chain.

In other words, the T-shaped heads are 55 overlapped by portions of the projections 14.

In practice one hook 9 is reversely bent or twisted to that of the other substantially as shown, described and claimed in my co-pending application filed July 29, 1919, 60 Serial No. 314,069, whereby in use the twisting of the cross chain on the shoe is materially prevented, that is to say, the outer end of each hook 9, which forms an inwardly extending upper or lower hook 65 portion, is bent or twisted laterally from a

position parallel to the link to a laterally inclined position. Thus, the upper hook portion of hook 9 at the left of Fig. 8 is twisted laterally to the right, whereas the lower hook portion of hook 9 at the right 70 of Fig. 8 is twisted to the left. Hence, one hook is reversely bent relatively to the other, and the outer end of each is turned out of alignment with the longitudinal axis of the cross chain. This construction, as heretofore pointed out, provides an effectual way to prevent the cross chain from turning, as hitherto in use it has been found that cross chains have a constant tendency to turn from a flat position to either side. 75

The various details may be more or less changed without departing from the spirit or scope of the present improvement as defined by the appended claims.

I claim as my invention:

1. A center link for an anti-skid cross chain comprising a relatively wide body portion having a plurality of spaced locking projections at each side and also having a pair of narrow eye-forming portions 90 terminating in heads, the latter adapted to be overlapped by the locking projections, a pair of said locking projections also bent in the direction of the length of the center link to overlap the inner edges of each head. 95

2. A center link for an anti-skid cross chain comprising a relatively wide body portion having at each side a plurality of locking projections spaced apart and having at its ends a pair of relatively narrow eye-forming projections terminating in I-formed heads, the eye-forming projections being bent to bring the heads into engagement with the body, and the locking projections being bent to overlap such heads, and then 100 clinched over the inner edges of the heads adjacent to their juncture points. 105

3. A center link for an anti-skid chain comprising a body portion of sheet metal having a plurality of locking projections at 110 the outer edges thereof and also having a pair of eye-forming projections having enlarged ends, the eye-forming projections being bent to form loops and to bring the enlarged ends into contact with the body of 115 the link, and the locking projections being bent to overlap the enlarged ends of the eye-forming projections one of said locking projections and an enlarged end being interlocked by forcing a part of the first over 120 an edge of the second.

4. A center link for an anti-skid chain comprising a body portion of sheet metal having a locking projection at each side and also having a pair of eye-forming projections having enlarged ends, said eye-forming projections being bent to form loops and to bring the enlarged ends into contact with the body of the link, and the locking projections being bent to overlap the en- 125 130

larged ends of the eye-forming projections, said locking projections also being clinched over the inner edges of the enlarged ends, and said center link being also bent transversely of its length thereby to conform substantially to the shape of a tire.

5. A center link for an anti-skid chain comprising a body portion having a locking projection at each side and also having a pair of loop-forming portions provided

with heads and adapted to be overlapped by the locking projections, portions of said locking projections being bent relatively to the remaining portions thereof to overlap the inner edges of the heads.

15

Signed at Wentworth, Province Ontario, Dominion of Canada, this 3rd day of April, 1920.

RUDOLPH W. EVANS.
